APPARATUS FOR RECEIVING TELEVISION PICTURES

Application filed November 12, 1929, Serial No. 406,632, and in Germany November 22, 1928.

The object of the invention is a television receiver based upon the well-known principle of synchronous decomposition or analysis and re-creation or re-composition of the picture at the sending and the receiving ends, respectively, and the transmission thereof through electric telegraph impulses. The invention by the aid of comparatively simple means of reduced dimensions of the elements required for picture re-creation makes it possible to produce at the receiving end luminous pictures of sufficient fineness.

In connection with the use of the Nipkow disk, the simplest light-control means heretofore known in receiver apparatus consists of a neon or other type of glow-discharge lamp having a luminous cathode presenting a surface equal to the picture field of the Nipkow disk. However, the luminous intensity of the picture built up successively from surface elements or units is low because of the fact that of the aggregate luminosity of the glow-discharge lamp in each case only the small fraction reaches and impresses the eye of the viewer which corresponds to the ratio between the hole in the Nipkow disk and the picture field.

The aim and object of this invention is, therefore, to increase the luminosity obtainable by the aid of glow-discharge lamps acting as receiver relays by providing means such that a larger part of the aggregate light which is given off from the lamp will be allotted to the unit divisor disk. This end is attained by concentrating or contracting the luminous flux issuing from a suitable shape of a controlled light source upon the area approximating a picture line, through the use of appropriate optical means to be hereinafter described. At the same time, the light is moved in such a way that this concentrated light will only impinge upon the picture line just being scanned by any appropriate form of scanning or distributor disk.

Details of the invention can be seen from the following specification of an embodiment shown by way of example in the accompanying drawing; wherein:

Fig. 1 represents a schematic perspective

of a receiver system according to my invention;

Fig. 2 shows a side view of the receiver of Fig. 1 and diagrammatically illustrates a preferred form of scanning disk; and,

Fig. 3 shows a suitable light source for use with a receiver of the type shown by Fig. 1.

As shown in Fig. 1, a perforated spiral disk 1 serves for the picture-point distribution. The disk 1 is rotated at a high rate of speed by a synchronous motor 2 which is maintained in synchronism by any desired means with the corresponding scanning or exploring device mounted at the sending end, such that the speed of the disk may be, for instance, 32 revolutions per second. In order to insure a finer division of the picture and still keep the disk dimensions down, the holes or apertures are disposed in the form of a double spiral so that, as shown, the whole picture is produced in the course of two rotations. Hence, by the above illustrated example, the number of transmitted pictures per second is 16, although by appropriate increases or decreases in the disk speed, the number of complete pictures transmitted per second may be increased for decreased to suit conditions.

For the light concentration, as described, and for the travel of the light flux, a drum 3 is provided, which has supported upon its circumference eight cylindrical lenses, for example, each being parallel to the axis. These lenses are shown in Figs. 1 and 2 only partially and are identically denoted by numerals 4. They are at the same distance from one another.

Parallel to the axis of rotation of the drum 3 is an elongated tubular or slit-shaped glow-discharge lamp 5, the luminosity of which is controlled by the televiser receiver 26 as to its brightness so that thereby the change between light and dark is produced in the incoming picture in well-known manner. The said luminous source 5, which has its rear face suitably mirrored or provided with a reflecting deposit or which is bodily fitted into a mirror, is pictured or reproduced by the rotating rim of cylindrical lenses 4 in the plane of the perforations of the disk 1. This

reproduction is at such reduction in size that its image covers a surface corresponding approximately to the product of length and width of a line of holes. However, since the lines of holes in the disk in the case here assumed is a shallow arc, it will be necessary that the field illuminated or scanned by the image of the luminous source 5 upon the disk 1 must be correspondingly wider than a line of holes. However, the tubular or slit-shaped light source 5, as shown in Fig. 3, may be given an arcuate curvature so that the image through the cylindrical lens is likewise curved in such a way that it will adhere and be adapted to the curvature of the picture lines. In this manner, the light upon the disk 1 can be condensed slightly more and the luminous source can be utilized still further.

If the rim of cylindrical lenses, by the aid of the worm-wheel gear 8, 9, and the transmission gearing 10, 11, 12 (by means of a perforated tape) is set into rotation, then the linear image of the luminous source 5 travels a certain distance upon the surface of the disk 1, in the direction indicated by the arrows from the top to the bottom until the next cylindrical lens occupied the location of the preceding one, when the cycle is repeated over again. In order that this migrating image of the light source 5 may fall upon the disk 1 always just at the height or level of the particular line just undergoing scanning, there must be a definite relation between the speed of the disk 1 and that of the rim or circle of lenses 3, 4. In the example here given where it is assumed 16 pictures are reproduced each second, the rim of lenses must just make two revolutions per second.

The migrating picture of the luminous source 5, in the arrangement here shown, describes a circular path in the plane of the drawing. Thus, if the picture is to be uniformly sharp and luminous upon the scanning or distributor disk 1, no matter what the height or level or what the picture line, it will be seen that the disk 1 should not be a planer surface, but it must inside the peripheral range of the double perforation spiral be toroidally curved all around as shown in Fig. 2. By the eccentric disposition of the light source 5 (Fig. 2), however, the curvature of the picture path may be flattened down with the result that toroid 13 and thus also the curvature of the picture can be made flatter. It is a suitable scheme to cover or fill up the pictures of the disk 1 with a light diffusive medium which, inside the whole angle formed between the traveling picture line and the eye of the observer, luminesces uniformly in all directions. The luminosity, in the presence of equal value of the electric control impulses, will then appear equal to the stationary eye throughout

the picture, that is to say, the same above as below, right and left.

The luminous source 5, as in Fig. 3, is constructed as, or consists of, a straight or still better an arcuate luminous tube with terminal electrodes 6 and 7, filled with a highly luminous gas such as a neon-helium mixture at a suitable pressure. The ensuing light even at a few millamps will be intensive enough to result in luminous pictures. By choosing different gas fillings for the tube, it is possible to reproduce the pictures in many different colors. The diameter of the luminous tube of 5 amounts, for instance, suitably to 5 mm. when the cylindrical lenses insures a reduction of 4:1 and when the holes in the distributor disk 1 have a diameter of 1 mm. The disk is then slightly moved out of the picture plane, and as a result uniform luminosity is obtained along an entire arc of the holes in the picture field. When the tube 5 has an arcuate curvature blurred images may be dispensed with. For reasons of safety, however, the luminous tube of 5 may be chosen of a somewhat larger diameter, and then it will be advisable to operate with as large a current as possible in order to compensate for the smaller concentration of the light. Instead of making the light source tubular and of utilizing the light column incidentally produced, it is also possible to use a cathodic glow-discharge between two closely adjacent or opposite electrodes the length of which should correspond to that of the luminous tube or the cylindrical lenses 4. What will then be produced in the plane of the disk 1 is a long strip of uniform cathodic glow. Such a glow-discharged lamp having a more or less narrow electrode gap offers the advantage of lower ignition and operating potential with an incidental facilitation in operation of the receiver amplifiers.

It will be apparent from the above description that the invention is capable of many modifications, and I believe myself entitled to make and use any and all of such modifications as fall fairly within the spirit and scope of the hereinafter appended claims.

Having now described my invention, I claim:

1. In a television system, a rotary scanning disk for tracing point for point intensities of light and shadow in a line for line manner for rebuilding a picture, and a drum provided with elongated lens elements about an axis at right angles to the axis of rotation of said scanning system for causing light issuing from a source internally thereof to trace successive parallel paths across the said scanning element during the rotation thereof.

2. In a television system, a rotary scanning element for tracing point for point intensities of light and shadow in a line

for line manner for rebuilding a picture, and a secondary scanning element revolving about an axis at right angles to the axis of rotation of said first element, and a plurality of elongated cylindrical lens elements positioned in the rim of said secondary scanning element for causing light beams issuing from a source of fluctuating intensity to focus upon said first element to trace successive parallel paths of concentrated light across the said scanning element during the rotation thereof.

3. In a television system, a scanning element adapted to be rotated in such a manner as to cause light beams projected thereon to trace successive parallel paths for rebuilding a picture subject, a drum provided with cylindrical lenses carried upon the outer edge thereof associated with said scanning element and adapted to rotate at a predetermined speed relative thereto about an axis at right angles to the axis of rotation of said scanning element, a source of light contained within said lens drum, and means provided by said lens drum for so focusing the light issuing from said source as to trace successive light paths across said scanning element for concentrating substantially the entire amount of light available from said source within a narrow portion of the total area covered by said scanning element.

4. In a television system, a scanning element adapted to be rotated in such a manner as to cause light beams projected thereon to trace successive parallel paths for rebuilding a picture subject, a lens drum associated with said scanning element, said lenses being arranged to focus over a width corresponding to the rebuilt picture width, a light source within said drum, and means for rotating said drum about an axis at right angles relative to the axis of rotation of said scanning element at a speed such that light beams passing therethrough are focused along successive parallel paths across said scanning element during each rotation thereof, whereby substantially the entire amount of light available from said source is concentrated upon each of the said scanning elements during the rotation thereof before said light source.

5. In a television system, a scanning element provided with a series of scanning elements about the outer periphery thereof and so arranged as to cause light beams projected thereon to be directed in successive substantially parallel paths, a lens drum associated with said scanning disk and having a plurality of cylindrical lenses about the surface thereof, an elongated source of light contained within said lens drum for directing light outwardly through the lens portion thereof, means for revolving said lens drum and said scanning element at a predetermined speed relative to each other, and means provided by the lenses in the outer periphery of

said lens drum for causing the light issuing from the said source contained therein to trace parallel paths across said scanning element during the rotation thereof, whereby substantially the entire amount of available light is periodically concentrated upon each path of projected light from said scanning element.

6. In a television system, a scanning element provided with a series of apertures about the outer periphery thereof arranged in a spiral manner, a lens drum associated with said scanning disk and having a plurality of cylindrical lenses about the surface thereof, an elongated source of light contained within said lens drum for directing light outwardly through the lens portion thereof, means for revolving said lens drum and said scanning element at a predetermined speed relative to each other, and means provided by the lenses in the outer periphery of said lens drum for causing the light beams issuing from the said source contained therein to focus upon successive parallel paths across said spiral scanning element during the rotation thereof, whereby substantially the entire amount of available light is periodically concentrated upon each path of projected light from said scanning element.

7. In a television system, a scanning disk provided with a plurality of scanning elements arranged in a spiral path about the outer periphery thereof for causing light beams passing therethrough to trace successive parallel paths for rebuilding a picture, a source of light adapted to be varied in intensity in accordance with received signalling impulses, and a lens drum rotating about an axis at right angles to the axis of rotation of said scanning element interposed between said light source and said scanning element for causing the light issuing from said source to be successively concentrated along substantially parallel paths corresponding to the path traced by each individual scanning element thereacross during the rotation of said scanning element and lens drum relative to each other.

8. In a television system, a toroidal-shaped scanning disk having a plurality of apertures arranged in a spiral path about the outer periphery thereof, means for rotating said scanning element at a predetermined speed, a drum provided with a plurality of elongated lens members mounted about the outer periphery thereof, means for rotating said drum about an axis substantially at right angles to the axis of rotation of said scanning element and at a predetermined speed relative thereto, an elongated light source of a length substantially equal to the width of a picture represented by the spacing of said scanning elements arranged within said drum, and means provided by said elongated lenses about the outer periphery of said drum for

causing light issuing from said source to be concentrated along successive paths substantially corresponding to the path traced by each aperture of the spiral disk rotating relative to a fixed point, whereby the effective amount of available light for rebuilding a picture is substantially increased.

9. In a television system, a rotatable scanning disk having a plurality of apertures arranged in a spiral path about the outer periphery thereof, a rotatable drum disk rotating relative to said scanning disk about an axis at right angles to the axis of rotation of said scanning disk, an elongated arcuate-shaped light source contained within said drum disk, means for varying the intensity of said light source in accordance with received signalling impulses, a plurality of elongated lens elements arranged in the outer periphery of said drum disk for directing the light issuing from said light source toward said scanning disk and concentrating the light from said source so as to form a succession of substantially parallel lines corresponding to the lines traced by the rotation of the various apertures of the spiral forming said scanning disk, whereby the illumination on the rebuilt image is increased.

10. In a television system, a rotatable scanning disk having a plurality of apertures arranged in a spiral path about the outer periphery thereof, a rotatable drum disk rotating relative to said scanning disk about an axis at right angles to the axis of rotation of said scanning disk, an elongated arcuate-shaped light source having a curvature corresponding to the curvature of the path traced by each individual aperture of said scanning disk contained within said drum disk, means for varying the intensity of said light source in accordance with received signalling impulses, a plurality of elongated lens elements arranged in the outer periphery of said drum disk for directing substantially the entire amount of light issuing from said source towards said scanning disk and concentrating the light from said source so as to form a succession of light paths corresponding to the lines traced by the rotation of the various apertures of the spiral scanning disk, whereby the illumination of the rebuilt image observable upon viewing the scanning disk is increased substantially.

11. In a television system for the electro-optical reproduction of television images, a drum scanning disk having a plurality of elongated lens elements carried upon the periphery thereof, a light source supported within said lens drum and extending transverse thereto for a distance at least equal to the width of said lens elements, means for rotating said lens drum at a predetermined speed, whereby the image of said light source is caused to trace in succession a plurality of separate paths of light varying in intensity

in accordance with the varying intensity of the light issuing from said light source, a toroidal-shaped scanning disk having a plurality of apertures therein arranged along a spiral path, means for rotating said toroidal disk about an axis at right angles to the axis of rotation of said lens drum, and means provided by said toroidal-shaping of said scanning disk for adapting the disk to the path of the image of the luminous source traced by the rotation of said drum disk, whereby illumination of the rebuilt image is increased substantially.

CERTIFICATE OF CORRECTION.

Patent No. 1,884,287.

October 25, 1932.

FRITZ SCHROTER.

It is hereby certified that error appears in the printed specification of the above numbered patent requiring correction as follows: Page 1, line 77, for "for" read "or"; page 2, line 28, after "lens" insert the word "has", and line 121, claim 1, after "elements" insert the word "revolving"; and that the said Letters Patent should be read with these corrections therein that the same may conform to the record of the case in the Patent Office.

Signed and sealed this 28th day of February, A. D. 1933.

M. J. Moore,

Acting Commissioner of Patents.
